UNITED STATES PATENT OFFICE.

WILLIAM KLEHR, OF FOREST HILLS, NEW YORK, ASSIGNOR TO EDWARD F. CALDWELL & CO. INC., OF NEW YORK, N. Y., A CORPORATION OF NEW YORK.

DESIGN FOR AN ELECTRIC-LIGHT FIXTURE.

Application filed May 15, 1928. Serial No. 26,678. Term of patent 3½ years.

To all whom it may concern:

Be it known that I, WILLIAM KLEHR, a citizen of the United States, and a resident of Forest Hills (Long Island), borough of Queens, in the county of Queens and State of New York, have invented a new, original, and ornamental Design for Electric-Light Fixtures, of which the following is a specification, reference being had to the accompanying drawings, forming part thereof.

Figure 1 is a front elevation of an electric light fixture showing my new design; and Figure 2 is a plan view of Figure 1.

I claim:

The ornamental design for an electric light fixture as shown.

Signed at New York in the county of New York and State of New York this 10 day of May, A. D. 1928.

WILLIAM KLEHR.
